(57) **CLAIM**

The ornamental design for alarm clock speaker system for media player, as shown and described.

DESCRIPTION

FIG. 1 is a front, right side, perspective view of an alarm clock speaker system for media player showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a cross sectional view thereof on line 8—8 in FIG. 2; and,

FIG. 9 is a cross sectional view thereof on line 9—9 in FIG. 2.

The broken line showing is of environmental material and forms no part of the claimed design.
